UNITED STATES PATENT OFFICE

CARL JOHAN OSCAR BERGSTROM, OF HUSKVARNA, SWEDEN

CATTLE DRINKING CUP OR THE LIKE

Application filed August 30, 1930, Serial No. 478,908, and in Sweden September 2, 1929.

The present invention has for its object a mounting arrangement for drinking cups or the like. More particularly it refers to cattle drinking cups used in farm yards or the like where a plurality of watering places have to be disposed within the same building.

In such plants it is customary to dispose all or at least a certain group of the drinking cups on the same level so that said cups may 10 easily be supplied with water from a common container communicating with the cups through a feeding pipe. Said container is then usually provided with a float device of known construction which automatically 15 maintains the water level in the container and thus also in all the drinking cups connected thereto at a suitable predetermined height.

It is previously known to dispose the cups in such a manner that they bear against the 20 feeding pipe and communicate with said pipe through feeding holes passing through the pipe wall and the cup wall in the contact surface between the pipe and the cup. Said known arrangement shows, however, the inconvenience that it will either be comparatively 25 complicated and unsteady or afford an unsatisfactory sealing against the feeding pipe.

The present invention has for its object to 30 eliminate said inconvenience and to bring about a mounting arrangement whereby one or more drinking cups in a short time may be disposed by any unskilled worker at any desired place along the feeding pipe while 35 using very simple tools, a very firm and sealing contact being then established.

The invention consists substantially therein that the portion of the cup surface, which bears against the pipe, partially surrounds 40 said pipe.

The invention will now be more closely described with reference to the accompanying drawing on which Figures 1 and 2 show an embodiment of a mounting arrangement, 45 whereas Figures 3 and 4 show another embodiment. Figure 5 shows the cup in top view in order to illustrate the disposition of the feeding holes. Figure 6 shows a third embodiment.

50 On the drawing a drinking cup 1 of cast

iron or the like is provided with a recess into which the feeding pipe 2 is inserted. Said recess is on its top provided with a concave surface 3 which at least at its upper portion closely conforms to the shape of the pipe 2 55 whereby a firm contact between the cup and the pipe is rendered possible. In the surface 3 one or more holes 4 are disposed, preferably when casting the cup, which holes communicate with the hole or holes 5 disposed in the pipe 3. If only one hole 4 is provided, it is 60 preferably given a rectangular shape. The interior of the cup thus communicates directly with the pipe 2 and, by way of example, also with a float controlled container 65 not shown on the drawing. To prevent leakage in the connection between the cup and the pipe a rubber packing or the like 6 is preferably inserted according to Figures 1 and 3.

The cup is below provided with a projecting portion or a flange 7 opposite the surface 3. The distance between the upper edge of the flange and the opposing edge 9 of the cup should then be somewhat greater than the diameter of the used feeding pipe so that said 75 pipe may be easily used. On the flange a squeezing or locking device 10 or 11 respectively is disposed which has for its object to hold the cup in the desired position along the pipe.

According to Figures 1 and 2 the locking arrangement consists of a bolt 10 tapped into the flange 7, the bolt head being easily accessible from the outside. The inner bolt end facing the pipe is then, upon tightening the 85 bolt, pressing the pipe 2 to bear against the surface 3 or the packing 6 respectively. It is then preferred to absorb the bolt pressure by an intermediate plate of suitable form.

According to Figures 3 and 4 the locking 90 arrangement comprises a wedge 11 inserted between the flange 7 and the pipe 2 and easily accessible laterally both when the wedge has to be forced into position and when it has to be removed. It is suitable to absorb the wedge 95 pressure by an intermediate plate 13 which is formed on top in conformity with the pipe and which below has an engagement surface adjusted to the angle of the wedge.

To further assure the holding of the cup 100

in position a number of holes 14 are disposed in the upper part of the cup, preferably above the highest allowable water level.

In mounting the cups in a farm yard or 5 the like, the following simple procedure may be followed. First of all, a single feeding pipe is mounted on a suitable level throughout all the stalls, whereupon some holes 5 are drilled in alignment on the upper side of the 10 pipe where a cup is to be disposed, then using by way of example an ordinary drill having a diameter of for instance six millimeters. Thereupon the cup together with its packing 15 6 is disposed on the pipe in such a manner that the holes 4 will register with the holes 5. Then the bolt 10 is tightened or the wedge 11 brought to firm engagement respectively and the mounting is ready. If desired, some screws are disposed in the holes 14. The 20 holes 5 may, of course, also be disposed after the cup has been secured onto the pipe.

It is then to be observed that the same construction of the cup may be used according to 25 the embodiment shown on Figures 1 and 2 as well as that shown on Figures 3 and 4. The difference resides solely in the locking device proper.

In Figure 6 there is shown a cup 1 mounted 30 in the same manner as before on the feeding pipe. This embodiment is differentiated from the previously described embodiments by that an airtrap 16 is disposed between the inlet apertures 4 and the interior of the cup 1. Said trap is formed by a partition 15 disposed according to the drawing.

The invention is of course not limited to 35 drinking cups but may of course be applied everywhere, where an easy and handy mounting of water cups is desired along a feeding pipe. It is also conceivable that similar arrangements may be used also in case the feeding pipe should extend in other directions than the horizontal direction.

I claim:

40 1. A cattle drinking cup comprising a cup-shaped member at least partially surrounding a feeding pipe, said feed-pipe having a plurality of small openings in its upper side, said cup-shaped member having one relatively large opening directed downwardly and registering with all the said small openings in the upper side of the pipe.

45 2. A cattle drinking cup as described in claim 1, characterized by having a squeezing and locking device disposed on a projection from said cup substantially opposite the feeding holes in the pipe, and operating to hold said pipe against said cup to prevent both 50 rotary and axial displacement.

55 3. A cattle drinking cup as described in claim 1, in which the cup is held in place on the feeding pipe by a bolt tapped into a flange projecting from said cup substantially opposite the feeding holes in said pipe, said bolt

pressing through the intermedium of a suitably shaped plate against said pipe.

4. A cattle drinking cup as described in claim 1, in which the opening into the cup is provided with air-trapping means which serve 70 to prevent back-flow.

In testimony whereof I affix my signature.

CARL JOHAN OSCAR BERGSTROM.
